(57) CLAIM

We claim the ornamental design for a framing square, as shown and described.

DESCRIPTION

FIG. 1 is a perspective view from above of an embodiment of the claimed design;

FIG. 2 is a top view of the claimed design of FIG. 1;

FIG. 3 is a bottom view of the claimed design of FIG. 1;

FIG. 4 is a left side view of the claimed design of FIG. 1;

FIG. 5 is a right side view of the claimed design of FIG. 1;

FIG. 6 is a rear view of the claimed design of FIG. 1;

FIG. 7 is a front view of the claimed design of FIG. 1;

FIG. 8 is a perspective view from above of another embodiment of the claimed design;

FIG. 9 is a top view of the claimed design of FIG. 8;

FIG. 10 is a bottom view of the claimed design of FIG. 8;

FIG. 11 is a left side view of the claimed design of FIG. 8;

FIG. 12 is a right side view of the claimed design of FIG. 8;

FIG. 13 is a rear view of the claimed design of FIG. 8;

FIG. 14 is a front view of the claimed design of FIG. 8;

FIG. 15 is a perspective view from above of another embodiment of the claimed design;

FIG. 16 is a top view of the claimed design of FIG. 15;

FIG. 17 is a bottom view of the claimed design of FIG. 15;

FIG. 18 is a left side view of the claimed design of FIG. 15;

FIG. 19 is a right side view of the claimed design of FIG. 15;

FIG. 20 is a rear view of the claimed design of FIG. 15; and,

FIG. 21 is a front view of the claimed design of FIG. 15.

The ornamental design which is claimed is shown in solid lines in the drawings: The broken lines in the drawings are for illustrative purposes only and form no part of the claimed design.

1 Claim, 15 Drawing Sheets
